US0D1106900S

(12) **United States Design Patent** (10) **Patent No.:** **US D1,106,900 S**
(45) **Date of Patent:** **** Dec. 23, 2025**

(54) **MOTOR VEHICLE AND/OR TOY REPLICA THEREOF**

(71) Applicant: **TOYOTA JIDOSHA KABUSHIKI KAISHA**, Toyota (JP)

(72) Inventors: **Takeo Sowa**, Miyoshi (JP); **Tung-Yen Tsai**, Irvine, CA (US); **Moto Takabatake**, Mountain View, CA (US)

(73) Assignee: **TOYOTA JIDOSHA KABUSHIKI KAISHA**, Toyota (JP)

(**) Term: **15 Years**

(21) Appl. No.: **29/932,757**

(22) Filed: **Mar. 15, 2024**

(30) **Foreign Application Priority Data**

Sep. 19, 2023 (JP) ..... 2023-019072 D

(51) **LOC (15) Cl.** **12-08**
